SELECTING SYSTEM USING A SINGLE MAGNET

Application filed October 31, 1931. Serial No. 572,363.

This invention relates to selecting mechanism of the character in which a plurality of selector elements is controlled from a remote point. It more especially relates to 5 magnetic distributors employed in the receiving units of printing telegraph systems wherein a plurality of mechanical operations is selectively controlled from a remote point.

An object of the invention is to provide 10 a simplified selecting mechanism for the receiving units of printing telegraph systems.

A feature of the invention is the provision of a magnetic distributor having a winding and a shaft carrying a pole piece, at 15 least one of these elements being rotatable to control a number of armatures of a magnetic system.

Another feature of the invention resides 20 in the provision of a magnetic distributor having a winding and a shaft carrying a pole piece and wherein there are a plurality of magnetic circuits available for controlling the operation of a series of armatures one at a time and in succession.

25 Other features and advantages will be apparent from the following description and appended claims.

For the purpose of illustrating the genus 30 of the invention, a few embodiments thereof are shown in the accompanying drawing, in which:

Fig. 1 is a central sectional view of a magnetic distributor according to one embodiment of the invention;

35 Figs. 2 and 3 are similar views of other embodiments of the invention;

Fig. 4 is an end view along line 4—4 of Fig. 1;

Fig. 5 is a similar view along the line 5—5 of Fig. 2; and

Fig. 6 is a fragmentary section taken along line 6—6 of Fig. 2.

Referring to Figs. 2, 5 and 6 wherein one embodiment of the invention is illustrated, 45 numeral 11 designates a rotatable shaft which carries a pole piece 12 and positions the same in front of several armatures 13, 14, 15, 16 and 17 of stationary magnet windings 20, 21, 22, 23 and 24, respectively.

50 Each armature engages a selector or latch

pin 25 to operate the same, the movement of pins 25 being limited by a pair of stop collars 26 and 27 fixed to each pin and engageable with a stationary part 28. The armatures are biased into unoperated position by a spring 30. Each latch pin 25 serves to hold a printer member or permutation bar 31 in the unoperated position against the biasing effect of a spring 32.

Each of the other armatures carries a similar selector 25 and controls the operation of its individual member 31. The shaft 11 provides a common magnetic return circuit for the stationary magnets. The core designated 33 affords a fulcrum for the armature associated with each magnet.

If the windings 20 to 24 inclusive are energized at the time pole piece 12 comes opposite an armature, the latter will be attracted, pulling its selector to the left, as 70 viewed in Fig. 2, and releasing member 31 associated therewith. The other armatures will be similarly attracted when the pole piece 12 is positioned opposite an energized winding, and the other selectors 25 actuated, 75 as before. The selectors 25 and members 31 are restored to latched position by means not shown. In the above description it has been assumed that the windings 20 to 24 inclusive were connected in series. However, 80 only that armature will be attracted that is in front of a pole piece 3, since the air gap for all other magnets is such as to reduce the pull below that required to operate the armature against the pull of the retractile 85 springs 30.

With the windings 20 to 24 inclusive connected in series and to the circuit of the incoming line section, considerable undesirable inductance would be added in the circuit. 90 This could be eliminated by having a contacting device on shaft 11 which would short-circuit all coils except the one whose armature is in front of the pole piece 12. Under this condition only a single winding would be in circuit at any given time.

Another method of eliminating the undesirable inductance is shown in Fig. 2 in which the coils 20 to 24 are energized individually through a rotating commutator disc 34. The 100

body of this disc is of insulating material and has an annular contacting ring 35 embedded in and flush with one face thereof. A segmental contact 36 integral with or electrically connected to the ring 35 is arranged flush with the opposite face of the disc. Disc 34 is mounted on shaft 11 so as to rotate therewith and have segmental contact 36 facing the magnets to engage brushes 37. Each one of the latter brushes is connected to one terminal of each magnet winding. The other terminal of each of the windings is grounded as indicated at 40. A brush 41 connected to ring 35 with an incoming line section circuit 42.

From the foregoing description it will be seen that, if the pole piece 12 is rotated in synchronism with incoming signals, these signals will be distributed and caused to operate those armatures corresponding to the marking portions of the signal. Thus, members 31 may be selectively released to operate printing mechanism of a printing telegraph receiver. The shaft 11 may be driven by any suitable start-stop clutch mechanism in a manner well known in the art, or by any practicable electric or other motor.

Since the arrangement above described, wherein the windings are in series, is, in effect, a single magnet providing five distinct magnetic circuits and but one winding may be placed in circuit at a time by either of the above described methods, it is evident that a similar result would be obtained by placing a single winding around the common magnetic return path. Such an arrangement is shown in Figs. 1 and 4 wherein a single winding 45 is disposed about a rotatable shaft 12. In this arrangement, as before, although but a single winding is used, there are five distinct magnetic circuits. However, only one of these magnetic circuits is effectively completed at a time, so the results accomplished are essentially those described in connection with Figs. 2, 5 and 6. Like parts in Figs. 1 and 4, and 2, 5 and 6 have been given the same numerals, and, as the operations of the two arrangements are practically the same, the operation of the second arrangement will be clear from the above description of the first embodiment.

Referring to Fig. 3, a third arrangement embodying the invention is disclosed. In this arrangement a shaft 51 carries a single winding 46 upon the eccentrically bent portion 47 thereof, so that the winding is brought successively into operating position in front of several armatures 53 upon rotation of the shaft. But one armature, indicative of a plurality of armatures, is illustrated in this figure, and it is pivoted at 48 to a standard 50 and is biased to unoperated position by a spring 30, except when winding 46 is positioned in front of that particular armature 60 and is energized from a line section circuit 42.

The winding is energized through a commutator disc 54 comprising two rings 55 and 56 mounted in an insulating material, and each connected to one terminal of winding 46. Rings 55 and 56 engage two brushes 57 and 58 which are connected one to a line section circuit 42 and the other to ground, as indicated at 60. The armatures are successively operated to move selectors 25 and release a plurality of printer members 31, as in the other two embodiments previously described.

As many changes could be made in the above described arrangement, and many apparently widely different embodiments of this invention could be made without departing from the scope thereof, it is intended that all matter contained in the above description or showing shall be interpreted as illustrative and not in the limiting sense.

What is claimed is:

1. In a magnetic distributor, the combination of an electromagnet having a stationary winding and a movable pole piece, a plurality of armatures for said magnet and a shaft forming a portion of the magnetic circuit of said magnet for rotating said pole piece into operative positions relative to said armatures for successively controlling their operation.

2. In a magnetic distributor, the combination of a magnet having a stationary winding adapted to be energized in response to received signal impulses, a movable pole piece and a plurality of armatures for said magnet and a shaft forming a portion of the magnetic circuit of said magnet for rotating said pole piece into successive and operative positions relative to said armatures to selectively control their operation in accordance with the energization of said winding.

3. In a magnetic distributor, the combination of an electromagnet having a stationary winding, a plurality of armatures for said magnet, a pole piece rotatable with respect to said winding and a shaft forming a portion of the magnetic circuit of said magnet for rotating said pole piece in synchronism with received signals and positioning said pole piece to successively control the operation of said armatures in accordance with the energization of said winding.

4. In a magnetic distributor, the combination of a plurality of stationary windings adapted to be selectively energized in response to received signal impulses, an armature for each winding, a movable pole piece and a shaft for rotating the same in synchronism with received signals to operative positions relative to said armatures for successively controlling their operation.

5. In a magnetic distributor, the combination of an electromagnet, a plurality of armatures for said magnet and a shaft rotating in synchronism with received signal elements, said shaft forming the core of said electromagnet and having an eccentrically

mounted portion adapted to be operatively positioned relative to said armatures for successively controlling their operation in accordance with impulses received by said elec-
5 tromagnet.

6. In a telegraph receiver, an electromagnet comprising a solenoid and a core therefor formed by a shaft adapted to rotate about its axis in synchronism with received signals, a plurality of armatures radially disposed around said shaft as a center, and a pole piece eccentrically mounted on said shaft, said pole piece being adapted when rotated to successively control the operation
10 of said armatures in accordance with received signals.

In witness whereof, I hereunto subscribe my name this 19th day of October, 1931.

ALLISON A. CLOKEY.
